METHOD AND APPARATUS FOR MAKING
NONMETALLIC SHEATHED CONDUCTORS

Charles W. Abbott, Larchmont, N. Y.

Application August 2, 1941, Serial No. 405,181

4 Claims. (CL 57—7)

This invention relates to electrical conductor construction, illustratively of the type intended for installation in buildings to form the circuit or circuits usually for lighting, power, and like uses, and more particularly, to an apparatus and method for making such electrical conductor construction. This application is a continuation, in part, of my application Serial No. 350,194, filed August 3, 1940, since matured into Patent No. 2,251,262 of August 5, 1941.

One of the objects of this invention is to provide a method and apparatus for making insulated conductor constructions of the above-mentioned character in a simple, efficient and economical manner. Another object is to provide a method and apparatus for building up an insulating covering or sheathing for a wire or electrical conductor, including one or more elements that are in tape-like form and helically wrapped, in which certain complications of both operation and construction that are inherent in present methods and apparatus, may be dependably eliminated. Another object is to provide a method and apparatus in which an insulating or like covering may be built up about a conductor, or the like, in which adjustment of factors like speed of drive of the winding or wrapping head and in which cost-increasing speed change mechanisms for achieving such adjustments, necessary in present-day machines to compensate for various or varying diameters, may be dependably eliminated.

Another object is to provide a method and apparatus in which the many operational and structural advantages of fixed relative speeds of wire or cable movement and of rotary movement of the wrapping head or heads, throughout substantial changes in diameter of wrapping, may be achieved in a thoroughly dependable and practical manner. Another object is in general to simplify and improve heretofore known methods and apparatus for constructing a sheath about a core, such as a wire or conductor, and to provide a method and apparatus capable of meeting the requirement of winding or wrapping a covering element helically but for different diameters according to the needs of commercial production at less cost of operation, less first cost of apparatus, at greater efficiency and greater reliability. Other objects will be in part obvious or in part pointed out hereinafter.

The invention accordingly consists in the features of construction, combinations of elements, arrangements of parts, and in the several steps and relation and order of each of the same to

one or more of the others, all as will be illustratively described herein, and the scope of the application of which will be indicated in the following claims.

5 In the accompanying drawings in which is shown by way of illustration a preferred embodiment of the mechanical features of my invention.

Figure 1 is a plan view of an insulated conductor or cable construction, with parts progressively removed or broken away or shown in section to show the various elements and their structural interrelationships, illustrating one form of conductor construction which may be made according to my invention;

10 Figures 2 and 3 are views diagrammatic of the conductor construction of Figure 1 showing two identical conductor constructions, but, respectively, of different radial dimensions to illustrate certain features of how my method and apparatus cope with the different radial dimensions required in different sizes or relative dimensions of conductor construction;

15 Figures 4^a and 4^b show respectively the right-hand half and the left-hand half of a side elevation of a complete illustrative apparatus for carrying out my method, certain parts being indicated schematically or diagrammatically;

20 Figure 5 is a central longitudinal vertical sectional view on an enlarged scale of part of the apparatus of Figure 4 showing its relation to the conductor being operated upon; and

25 Figure 6 is a diagrammatic plan view of an applicator embodied in the apparatus of Figure 4, as seen along the lines 6—6 of Figure 4.

30 Similar reference characters refer to similar parts throughout the several views of the drawings.

35 For purposes of illustration, I have selected a form of conductor construction disclosed in my above-mentioned co-pending application, utilizing tape-like elements wrapped helically, and in Figure 1 the conductor 10, of any suitable size or construction, may have about it and preferably directly applied to it an initial layer of insulation indicated at 12, illustratively a layer of rubber or like compound, and of suitable thickness. Thereabout is wound a band or tape-like element 13 illustratively of paper, and if desired, and as disclosed in my said application, there may be interposed between the jacket 12 and the helical layer formed by the member 13, a coating 14, as of lacquer, particularly where the jacket 12 is of vulcanized rubber, to which is applied a material comprising small particles or flakes, indicated

at 14^a, preferably mica of suitable and preferably very small mesh, and a coating 15 of a suitable wax.

The tape element 13 may or may not, when helically wrapped, have an overlap of one turn on the next, and for greater simplicity I have shown the element 13 without an overlap and hence with the adjacent edges of successive turns abutting. In either case, and in the illustrative form of conductor shown, there is then applied over the paper wrap 13 a continuous helix of a cord-like element 17 wound at a pitch or lay to leave a suitable spacing between successive turns somewhat analogous to a form of screw thread. Member 17 may be substantially round in cross-section and is preferably of twisted paper, being thus a form of so-called paper cord and being of relatively tough or strong construction. Next there is applied to the structure, over and into the spaces between successive turns of the helical cord 17 an insulating material or compound that is plastic to a suitable degree throughout the operating ranges of temperature of the ultimate conductor construction and preferably the material is a relatively quick-setting thermoplastic so that it can be, when heated, more readily applied. Its composition and its method of application are preferably as described in my aforesaid application to which reference is to be made for further details. The layer formed by the cord 17 and the plastic 18 is of suitable thickness, the plastic 18 preferably having binding or adhesive qualities which, coupled with some impregnation of the paper wrap 13 and of the helical rib 17 forms a relatively tough, yieldable and readily flexible sheathing entity over which is now helically wound a tape or band-like element 19, preferably also of paper, and with or without an overlap, being shown in Figure 1, for greater simplicity, as being without an overlap and hence with the adjacent edges of successive turns abutting.

Next I may apply a coating of wax, indicated at 20 and thereafter any suitable additional covering or sheathing may be applied. For example, where a multiple conductor construction is desired as, for example, two insulated conductors contained within a single external sheath, I may run two constructions like that above described, side by side, as in Figure 1, where the additional structure is indicated by the reference character 21 whence an outer covering element 22, such as a braiding of cotton braid, may be applied after first applying a suitable sheet material like paper, as indicated at 23 about the two conductor structures, the paper element 23 functioning as a barrier or dam to block penetration of such braid-impregnating compound, such as compounds or saturants giving the braid covering 22 moisture-proof, fire-resistant and other characteristics, as it is desired to employ. The braid covering 22 may ultimately be given a finished coating as indicated at 24. Full details of such a construction are disclosed in my aforesaid application.

In making up insulated conductor constructions utilizing one or more wraps of a band or tape-like material, of which the helical elements 13 and 19 of Figure 1 may, insofar as the broader aspects of my present invention are concerned, be considered as illustrative, the diameter or radius of the helix to be wound necessarily varies as the size of any insulated conductor construction or cable of given structural characteristics and may vary also according to the type of cable

construction to be constructed. According to present day practice winding heads or flyers have to be provided with speed-change mechanisms usually capable of a wide range of change of speed, to meet such production requirements as changes in radius of the helix or helices, resulting not only in materially higher first cost and also maintenance of apparatus, but also in the necessity for somewhat precise adjustment and manipulation in operation, oftentimes requiring cut-and-try steps of adjustment with resultant wastage of time, labor and materials. Such disadvantages and shortcomings I avoid according to my invention and to better illustrate certain aspects of the latter reference might first be made to Figures 2 and 3, in Figure 2 of which, let it be assumed, the part or structure about which the first wrap, indicated at 13^a, corresponding to the element 13 of Figure 1, is to be helically laid, is of a diameter of 0.130", and it may comprise a conductor 10^a like the conductor 10 of Figure 1 with a suitable jacket 12^a thereover, like the jacket 12 of Figure 1, while in Figure 3 the corresponding elements 10^b and 12^b have an external diameter of 0.160" and are to have the helical element 13^b, like the element 13 of Figure 1, helically wrapped thereabout.

According to my invention and during movement axially of the cores about which the respective elements 13^a and 13^b are to be laid helically, I maintain a fixed relation between the rate of axial movement of the core and the number of turns of the helical element per unit length of core, for example, sixteen turns of the helical element per linear foot of core, but vary the width of the respective tape elements so that, as the angle of tape feed varies with increase in the diameters upon which they are served, there is laid along or longitudinally of the core a fixed diagonal dimension of the helical elements even though their individual widths are different. In Figures 2 and 3, four different widths of tape elements are shown, yet the above-mentioned diagonal dimensions, hereinafter called "diagonals," are all of the same magnitude, being indicated by the reference character Z. Where, for example, sixteen turns per foot of core are to be laid, I vary the just mentioned factors so that $\frac{3}{4}$ " diagonals of the tape elements, even though the latter are individually of different widths, extend lengthwise or axially of the core. With sixteen turns per foot, each turn thus accounts for covering a $\frac{3}{4}$ " increment of the core.

For example, with the core of Figure 2 having a diameter of 0.130", the tape element 13^a is of a width of $\frac{3}{8}$ ", but the angle of lay is such that a $\frac{3}{4}$ " diagonal of the tape element 13^a coincides with, geometrically speaking, an element of the cylindrical surface of the core about which the element 13^a is wound. But where the core diameter is 0.160", as in Figure 3, I use for the band or tape element 13^b a width of $\frac{7}{16}$ ", make the angle of lay larger (illustratively about 31° as at F in Figure 3 as compared with about 25° as at E in Figure 2), and thus achieve the laying of the element 13^b about the core with all of its $\frac{3}{4}$ " diagonals coincident with elements of the cylindrical core surface, thus maintaining sixteen turns of the helical tape element per foot of length of the core. In Figures 2 and 3 it may be assumed that the adjacent edges of successive turns are abutting though it will be understood that the same principles are em-

ployed for any degree of overlap of successive turns.

Where the conductor structures of Figures 2 and 3 are of the kind described above in connection with Figure 1, I apply the helical rib 17, also with a fixed number of turns per unit length, and where it is desired to get a closer spacing between adjacent turns of the rib element than, for example, the $\frac{3}{4}$ " spacing that would result from sixteen turns per foot of length, I prefer to wind simultaneously more than one rib or cord element, illustratively two of them, as indicated at 17^a and 17^b, spacing them $\frac{3}{8}$ " on center during the winding, and thus, for sixteen actual revolutions per foot of core, I achieve thirty-two turns of rib element spaced $\frac{3}{8}$ " center to center. One of these cords, as cord 17^a of Figures 2 and 3, coincides with or is disposed along the junction of adjacent turns of the underlying tape element, thus reinforcing or closing or sealing such junction.

With the rib element thus applied and the plastic 18 applied, representing a layer of the desired thickness, the diameter of the resultant core in the structure of Figure 2 may now be 0.240" and in the structure of Figure 3 may now be 0.265". About the former, the band or tape element 19^a, corresponding to element 19 is now helically applied, but is confined to sixteen turns per foot of core length and, due to the increased core diameter, I select a width of $\frac{1}{2}$ " for the element 19^a which, with an angle of lay of about 42° as at G, presents $\frac{3}{4}$ " diagonals lengthwise of and geometrically coincident with the elements of the cylindrical core surface. Upon the larger-diameter core of Figure 3 the band element 19^b, corresponding to element 19 of Figure 1, is applied, but again in sixteen turns per foot of core length, and here I give the element 19^b a width of $\frac{1}{8}$ " which, with the different angle of lay, about 43° as at H, fully covers the one-foot length of underlying core with exactly sixteen turns, again presenting $\frac{3}{4}$ " diagonals lengthwise of and coincident with the elements of the cylindrical core surface. In Figures 2 and 3, these diagonals are indicated at Z, being all of the same magnitude.

Thus whatever the radius of winding of the helical tape element, I maintain the same number of turns per unit length of the conductor structure, and achieve full coverage by the helical tape element by changing its width. In Figure 4, I have shown in side elevation a preferred form of apparatus to better illustrate certain of the unique advantages of my invention. Thus the apparatus may comprise a frame of any suitable construction, preferably having two upper spaced frame members 27 and 28 (Figures 4 and 6) preferably made of channel cross section and held in spaced relation by any suitable means not shown; suitable uprights, preferably in pairs, as indicated at 29, 30, 31, 32 and 33 form standards for the upper frame part 27-28, being also conveniently of channel shape and having spaced lower frame members 35 and 36, also preferably channel shaped, secured thereto for strength and rigidity of construction.

Supported by the paired uprights or standards 30, 31, 32 and 33 and preferably aligned along the longitudinal center line of the frame are bearings B in which is rotatably supported a main driving shaft 38 driven from any suitable source of motive power, illustratively and preferably an electric motor 39 which may be secured to a suitable support in turn secured crosswise

of the upper longitudinal frame members 27-28, the drive from the motor 39 to the shaft 38 being achieved in any suitable way as by the belt and pulley drive indicated at 40.

At the right hand end of the frame is supported a suitable guide pulley or sheave 42 over which the conductor or wire 10 is brought to the apparatus from a suitable source of supply such as a reel mounted on a let-off stand, not shown. From the guide sheave 42 the wire 10, in the present illustrative instance having thereon a jacket such as the jacket 12^a or 12^b of Figures 2 and 3, passes through the hollow shaft 43 which supports and rotates with it a paper pad flyer generally indicated by the reference character 44, the shaft 43 being rotatably supported in a suitable bearing structure 45 which bridges across and is secured to the upper frame members 27-28 and between the two bearings of which is accommodated a drive pulley 46 which is connected by belt 47 to a pulley 48 on the main drive shaft 38, a pulley 49 adjustably supported in any suitable way by the pair of uprights 33 serving as a means to keep the belt 47 at the desired tautness.

Illustratively, the speed of drive of the flyer 44 is 2,000 R. P. M. and the rate of movement of the conductor 10 in a direction toward the left is 125' per minute.

The flyer 44 may be of any suitable construction and is preferably of the type, known in the art, that takes and holds the roll or "pad" of band or tape-like element substantially coaxially with the axis of the flyer, and it is such a known type of flyer that is shown in Figure 4, feeding the paper element 13 onto and helically about the conductor core, being provided with suitable tensioning means and suitable means for adjusting itself, in known manner, to changes in the angle of lay. When rotating at 2,000 R. P. M. and with the conductor core traveling at 125' per minute, the flyer makes sixteen revolutions and hence applies sixteen turns of the tape element 13, per foot of conductor core.

To the left of the flyer 44 is a tube-like support 51, carried by the frame members 27-28 and aligned coaxially with the path of travel of the wire 10 which passes through it; support 51 has sleeved onto it a suitable number of rolls or pads, indicated at 52 of tape element 13 of the desired width so that, as soon as the pad in the flyer 44 is used up, a new pad from the storage supply 52 may be quickly slid off of support 51 and mounted in the flyer 44 without cutting the core, and thus to continue the winding operation.

Where the conductor is to have a helical rib like the rib element 17 of Figure 1, it next passes through the hollow shaft 53 of a flyer or head generally indicated by the reference character 54, shaft 53 being mounted in spaced bearings in a bearing structure 55 like the bearing structure 45 above described, there being a driving connection to the shaft 38 preferably by way of pulley 56 on the shaft 53, driven by belt 57 from a pulley 58 on the main drive shaft 38, and belt tightener pulley 59, suitably mounted adjustably in the standards 32 providing for maintaining the desired tautness on the belt.

The cord or rib flyer 54 may thus also be driven from the main drive shaft, at the above-mentioned speed of 2,000 R. P. M., thus also making sixteen revolutions per foot of wire core travel, but preferably the flyer 54, of known construction, applies two cord or rib elements simultaneously, in the illustrative embodiment being spaced

from each other $\frac{1}{8}$ ", thus in effect applying twice sixteen turns per foot of conductor core, as was described above in connection with Figures 2 and 3.

From the flyer 54 the conductor passes on toward the left through a tubular support 61, of suitable length to carry a suitable number of universally wound packages or "cops" 62 of the cord element 17. From the support 61, cop 62 may be slid off toward the right and into the flyer 54, as needed, the packages being double-wound or otherwise wound in any suitable way to provide the flyer 54 with two strands or cords, as indicated at 17^x and 17^y in Figure 4, where it is desired to wind a double helix as above indicated. One of them preferably overlies the helical junction of the underlying tape element.

Where the conductor structure is then to have applied to it a material like the plastic 18 above described in connection with Figure 1, the conductor structure next passes into and through an applicator tank or chamber 64 conveniently supported in between the two upper frame members 27-28, as appears better from Figures 4 and 6. The tank 64 contains the insulating material and also suitable means for insuring its application to the conductor structure. Thus the latter may enter the tank through a suitable guide opening or the like 65 in one end wall of the tank and then pass through a suitable device 66 suitably related to the opposite end wall, the device being in general of the type and form shown in Figure 5, and described in greater detail in my above-mentioned application. Thus it preferably comprises an internally tapered tube-like element having a land portion 66^a at its exit or left-hand end that is of uniform inside diameter somewhat less than the outside diameter of the helical rib 17 of the conductor structure so that the latter, as it is drawn therethrough, is subjected to some degree of compression, thus to compact the insulating material 18 into and about the conductor structure and also somewhat to compact the helical rib 17. These actions are aided by the tapered internal walls of the part 66 which guide the plastic material and the turns of the helixes 17^x and 17^y neatly and snugly into the restricted throat portion 66^a.

The moving core is submerged in the plastic compound 14 and to insure that it is applied to the ribbed structure, I may provide suitable means such as two spaced disk members 68 and 69 mounted within the tank 64 and suitably driven as by a shaft 70, the latter having, externally of the tank 64, a pulley 71 driven by a belt 72 from a motor 73 carried by the frame as indicated in Figure 4. The internal disk element or elements, as they are thus driven at a suitable speed, pick up and dispose over and onto the conductor structure suitable quantities of the plastic material which is indicated in Figures 5 and 6 at 14. Where the material is thermo-plastic, suitable means are provided for maintaining it in the tank 64 at an appropriate temperature and hence consistency and preferably also the member 66 is heated; such heating means are diagrammatically indicated in the drawings at 75 and 76 and may take any suitable form, being conveniently in the form of electrical heating units.

The conductor structure, now with its diameter substantially increased, passes on, leftward as seen in Figure 4, to have the next tape or band element such as the paper tape 19 of Figure 1 applied thereto and for this purpose a head or flyer like the flyer 44 above described may be em-

ployed. Thus the conductor structure passes through the hollow shaft 78 of a flyer generally indicated by the reference character 79, shaft 78 being rotatably supported in spaced bearings of a bearing structure 80 and having a driving connection to the main drive shaft 38, as by the pulley 81 on the flyer shaft 78 connected by belt 82 to pulley 83 on the drive shaft 38, and belt tightener pulley 84 adjustably carried in any suitable way by the pair of standards 30 insuring the desired tightness of the belt.

Through such a drive as this, flyer 79 is also driven at a fixed rate relative to the rate of movement of the conductor structure being built up and illustratively the flyer 79, with the conductor or core moving at 125' per minute, may have a speed of 2,000 R. P. M., thus making sixteen turns per foot of conductor and thus giving the tape element 19 sixteen turns per foot of conductor structure.

But since the core onto which the tape element 19 is wound is of materially greater diameter than that of the core about which the tape element 19 is wound, the width of the tape 19, carried in the form of a roll or pad by the flyer 79 is greater as is also the angle of lay, as will be clear from either Figure 2 or Figure 3, as above described.

Then the conductor passes on through a tubular member 86 suitably supported by the upper frame elements 27-28 and on this tubular member 86 is sleeved a suitable number of rolls or pads 87 of the tape element 19, of the desired width, ready to refill the head 78 when the pad in the latter is substantially used up.

Thence the conductor passes about a driven sheave or capstan 88 that is rotatably supported between the frame elements and the pair of standards 29, as by bearing blocks 89 carried by the uprights 29. Capstan 88 is driven from the main drive shaft 38 to give it a peripheral speed equal to the linear speed of travel of the conductor through the apparatus, illustratively 125' per minute, the conductor structure being taken one or more turns about the capstan to insure uniform rate of movement of the conductor structure, whence the latter passes on, as indicated at 90 to a suitable apparatus, driven in any suitable way, to reel up the conductor structure.

The capstan 88 may have any suitable driving connection with the main drive shaft 38 such as, for example, a worm 92 on the shaft 38 driving a worm wheel 93 on a shaft 94 extending transversely of the frame and provided with suitable bearing supports in auxiliary frame members generally indicated at 95; shaft 94 carries a spur gear 96 which drives a gear 97 of the capstan 88 through an intermediate gear 98 which may be carried in one end of an arm 99 pivoted to the shaft of the capstan 88 and provided with any suitable means as indicated at 100 whereby the intermediate gear 98 may be swung downwardly away from the spur gear 96 and thus interrupt the drive of the capstan.

With the flyers 44 and 79 thus driven to lay sixteen turns per foot of conductor travel at respectively different radii of winding, the tape elements 13 and 19 which they respectively wrap onto the structure are, for the respective radii of winding, of such widths that the sixteen turns completely cover the structure, with a uniform overlap throughout where an overlap is desired, or without an overlap and hence with adjacent edges of successive turns abutting. With the different widths of these two tape elements, illustratively the widths described above for elements 13^a and 19^a of Figure 2, the angles of lay become such

that $\frac{3}{4}$ " diagonals of the tape elements are laid parallel to the axis of the core structure and are laid substantially coincident with the geometric generating elements of their respective cylindrical core surfaces.

Were the widths of the two tape elements for heads 44 and 79 to be the same, a different number of turns per foot of core travel would have to be given the tape element of head 44, because of the smaller radius of winding, than would be given the tape element of head or flyer 79 which winds at a greater radius, and for each change in ratio of the several radii there would have to be a corresponding change in the relative speeds of the flyers and the rate of conductor core travel. Also, and as to any one flyer, its speed of drive would have to be changed, for a given width of tape element, were the radius of winding to be changed. According to prior methods and apparatus, complicated and costly speed change mechanisms have had to be employed to meet the varying requirements imposed by different radii of winding, and cumbersome and oftentimes time-consuming adjustments of speeds of drive have to be resorted to, and other disadvantages incurred. Thus, for example, an apparatus, according to prior practice, that would be called upon to produce successive lots of different sizes or styles of insulated conductor structure would have to be set or adjusted by the operators to operate at a considerable number of different flyer speeds and of relative speeds between flyers themselves, and speed change mechanisms had to be provided to meet such a wide variety of different combinations of conditions.

But according to my method and apparatus, I maintain fixed relationships, simplify greatly and make materially less costly the apparatus, and also greatly simplify the manual operation and supervision and control of the apparatus. Thus, for example, with a given ratio of drive of flyer head to rate of conductor core movement, I need only tabulate, for various diameters of conductor core and hence for various radii of winding of the tape element, the particular width of tape element with which to load the flyer, providing also a tabulation for any succeeding flyer in the same apparatus. Hence for a given radius of winding where only one flyer is employed or for the given radii of winding for the respective tape elements where several flyers are employed, the operator simply loads the one flyer in the one instance or the several flyers in the second instance with the corresponding width or widths of tape element, and lets the apparatus do the rest, while any subsequent requirement of change of radius of helical winding of a tape element again requires no adjustment or seeking for the right flyer speed, but requires simply the selection and loading of the particular flyer or flyers with the corresponding width of tape element.

Thus all the longitudinal dimensions Z of the various tape elements 13^a and 19^a of Figure 2 and 13^b and 19^b of Figure 3 are the same throughout and have the various radii or diameters of helical winding, and where one or more helical cord elements are employed, and with one of them such as cord element 17^a of Figures 2 and 3, having the same number of turns per unit length of core, is thus also brought into coincidence with the helical junction, whether it is an abutting junction or an overlapping junction, to hold the adjacent edges of adjacent turns securely in position and in effect to seal and close such junction and any

possible gaps or irregularities, where abutting, that may be present.

Thus, for example, where the size of conductor structure indicated in Figure 2 is to be made, flyer 44 is loaded with tape element 13^a of $\frac{3}{8}$ " width and flyer 79 is loaded with tape element 19^a of $\frac{1}{2}$ " width. When that lot of conductors is run off and should it then be necessary to run off a lot or quantity of conductor of the size indicated in Figure 3, the operator simply changes the loading of flyer 44 by loading it with $\frac{1}{8}$ " tape element 13^b and loads flyer 79 with $\frac{1}{8}$ " tape element 19^b, according to Figure 3. Of course, where the plastic applicator mechanism of Figures 5 and 6 is employed, the throat element 66 would, of course, be replaced by one of a differently diametered bore to suit such new requirements as thus arise. Preferably, and at suitably spaced points along the path of the core, I provide suitable means to steady the moving core and to prevent whipping or substantial vibration thereof as it moves along. A convenient location and support for such means, which preferably take the form of suitable bushings through the apertures of which the core passes, comprises the tubular supports for the storage of surplus tape or cord elements. Thus, for example, in the tubular support 61 in Figure 4^a, at the right hand end thereof, I mount a bushing 101, acting to steady the core during the action thereon of the flyer 54. A similar bushing 102 may be mounted in the right hand end of the tubular support 86 in Figure 4^b, to steady the now more massive core during action thereon by the flyer 79. These bushings preferably have tapered apertures as indicated with respect to the bushing 102 of Figure 4^b and by the tubular supports mounting them they are also aligned coaxially with the moving core.

Any suitable means may be employed to mount the bushings removeably and preferably their apertures are of such respective sizes that they can handle a suitable range of core diameters, thus to diminish the frequency of replacement thereof.

Thus it will be seen that there has been provided in this invention a method and construction in which the several objects hereinbefore noted together with many thoroughly practical advantages are successfully achieved. The method will be seen to be of a thoroughly practical character and well adapted to meet the varying requirements of commercial production of various types and sizes of insulated conductor and the apparatus will be seen to be greatly simplified, made available at lower first cost, can be more efficiently maintained and operated, and dependably eliminates the major disadvantages and shortcomings of heretofore known apparatus.

As many possible embodiments may be made of the mechanical features of the above invention and as the art herein described might be varied in various parts, all without departing from the scope of the invention, it is to be understood that all matter hereinabove set forth, or shown in the accompanying drawings is to be interpreted as illustrative and not in a limiting sense.

I claim:

1. In a method of applying helical wrapping to a conductive or insulating core, the steps which comprise moving the core axially along a given path at a given speed, helically winding at one point in said path a tape ele-

ment about said core in a fixed number of turns per unit length of core with the tape having a width sufficient to completely cover the core at the radius of winding determined by the diameter of the core in relation to the said fixed number of turns, helically winding at a subsequent point in said path a cord element over the taped core and then applying to the corded core a pliant mass of material and smoothing the latter during movement of the core, thereby increasing the core diameter, and helically winding at a still further point in said path a tape element of greater width than that of said first tape element onto the resultant larger-diametered core in the same number of turns per unit length of core as are given said first taped element, but with the said greater width of the tape element sufficient to completely cover the core at the greater radius of winding determined by the larger-diametered core in relation to the said same fixed number of turns per unit length of core.

2. In a method of applying helical wrapping to a conductive or insulating core, the steps which comprise moving the core axially along a given path at a given speed, helically winding at one point in said path a tape element about said core in a fixed number of turns per unit length of core with the tape having a width sufficient to completely cover the core at the radius of winding determined by the diameter of the core in relation to the said fixed number of turns, helically winding at a subsequent point in said path a plurality of cord elements about the moving core with the turns of the cord elements spaced axially along the taped core and each element being wrapped in a given number of turns per unit length of core, applying insulating means to the corded core and in the spaces intervening said axially-spaced cord elements, and helically winding at a subsequent point in said path a tape element of greater width than that of said first tape element onto the resultant larger-diametered core in the same number of turns per unit length of core as are given said first taped element, but with the said greater width of the tape element sufficient to completely cover the core at the greater radius of winding determined by the larger-diametered core in relation to the said same fixed number of turns per unit length of core.

3. An apparatus for insulating a conductor comprising a frame having means for supporting and drawing, at a given linear speed and along a given path, a wire core, said frame carrying a plurality of means spaced along said path for applying covering element to the core, one of said means comprising a source of supply of tape element and a flyer having means for driving it at a fixed R. P. M. in relation to the speed of movement of said core to helically wind said tape element about the core, whereby the width of the latter to be adequate to completely cover the core at the radius of winding is de-

termined by the diameter of the core and by the fixed number of turns per unit length of core resulting from the fixed relation of flyer R. P. M. to core speed, a source of supply of cord element of substantial thickness and a flyer for helically applying the cord element to the taped core with means for applying to the corded core a pliant mass of material and for smoothing it thereover during drawing movement of the core, thereby materially increasing the core diameter, another of said plurality of means comprising a source of supply of tape element and a flyer driven in fixed relation to the rate of drive of said first-mentioned flyer for helically winding said second-mentioned tape element onto the now larger-diametered core, whereby the width of said second tape element to completely cover the larger core at the latter's radius of winding is determined by whatever is the diameter of said larger core and by the fixed number of turns per unit length of core resulting from the fixed relation between the drive of said second flyer and the drive of said first flyer.

4. An apparatus for insulating a conductor comprising a frame having means for supporting and drawing, at a given linear speed and along a given path, a wire core, said frame carrying a plurality of means spaced along said path for applying covering elements to the core, one of said means comprising a source of supply of tape element and a flyer having means for driving it at a fixed R. P. M. in relation to the speed of movement of said core to helically wind said tape element about the core, whereby the width of the latter to be adequate to completely cover the core at the radius of winding is determined by the diameter of the core and by the fixed number of turns per unit length of core resulting from the fixed relation of flyer R. P. M. to core speed, means forming a source of supply for a plurality of cord elements of substantial thickness and flyer means for helically applying said cord elements to the taped core with the turns of the cord elements spaced axially along the taped core with means for applying to the corded core a pliant mass of material and for smoothing it thereover during drawing movement of the core, thereby materially increasing the core diameter, and another of said plurality of means comprising a source of supply of tape element and a flyer driven in fixed relation to the rate of drive of said first-mentioned flyer for helically winding said second-mentioned tape element onto the now larger-diametered core, whereby the width of said second tape element to completely cover the larger core at the latter's radius of winding is determined by whatever is the diameter of said larger core and by the fixed number of turns per unit length of core resulting from the fixed relation between the drive of said second flyer and the drive of said first flyer.

CHARLES W. ABBOTT.
